UNITED STATES PATENT OFFICE.

THOMAS JEFFERSON LEAGUE, OF CHICAGO, ILLINOIS, ASSIGNOR TO WOODRUFF & EDWARDS CO., OF ELGIN, ILLINOIS, A CORPORATION OF ILLINOIS.

DESIGN FOR A LAMP BASE.

Application filed April 17, 1926. Serial No. 17,324. Term of patent 3½ years.

To all whom it may concern:

Be it known that I, THOMAS JEFFERSON LEAGUE, a citizen of the United States, residing at Chicago, in the county of Cook and State of Illinois, have invented a new, original, and ornamental Design for Lamp Bases, of which the following is a specification, reference being had to the accompanying drawing, forming part thereof, wherein—base which incorporates my new design, substantially one-half of the ornamentation being completed, the unfinished portion within the marginal border being identical with the finished portion;

Fig. 2 is a side elevation thereof.

I claim:

The ornamental design for a lamp base, as shown.

THOMAS JEFFERSON LEAGUE.
